UNITED STATES PATENT OFFICE.

THOMAS B. DE FOREST, OF BIRMINGHAM, CONNECTICUT, ASSIGNOR OF ONE-HALF TO THE JOSEPH DIXON CRUCIBLE COMPANY, OF JERSEY CITY, NEW JERSEY.

LEAD-PENCIL.

SPECIFICATION forming part of Letters Patent No. 236,215, dated January 4, 1881.

Application filed March 13, 1880. (No model.)

To all whom it may concern:

Be it known that I, THOMAS B. DE FOREST, of Birmingham, in the county of New Haven and State of Connecticut, have invented a new Improvement in Lead-Pencils; and I do hereby declare the following, when taken in connection with the accompanying drawings, and the letters of reference marked thereon, to be a full, clear, and exact description of the same, which said drawings constitute part of this specification, and represent, in—

Figure 1, side view; Fig. 2, a vertical sectional view.

This invention relates to an improvement in lead-pencils such as are made from a cylinder of wood with a stick of lead through the center.

In many cases it is desirable to attach the pencil to a cord, as, for instance, to slates, books, and many other places; but the pencils as usually produced afford no convenience for such attachment.

The object of this invention is to provide the pencil with such means for attachment, which shall be a permanent part of the pencil; and it consists in the pencil provided with a perforated cap, through the perforation of which the cord may be secured, and as more fully hereinafter described.

A represents a common wood lead-pencil. B is a metallic cap, formed from sheet metal or other suitable material, struck up so as to closely fit one end of the pencil, and perforated at its closed end, as at a, and also with a side per-

foration, b. The end of the pencil should be 35 cut away, as seen in Fig. 2, so as to leave a clear passage from the perforation b to the perforation a, and the perforation b should be larger than the perforation a. This completes the pencil.

To attach the cord, pass one end through the perforation a, thence turning outward through the perforation b; then tie a knot or make other enlargement in the end of the cord, and draw such enlargement through the 45 perforation b, against the perforation a, as seen in Fig. 2, which secures the pencil to the cord in a neat and convenient manner. Instead of the side and end perforations, the perforation may extend diametrically through the cap, and 50 the cord be passed through and tied to itself, forming a loop in the cord through the cap.

By this construction I produce, as an article of manufacture and sale, a wood lead-pencil permanently provided with means for attaching to a cord.

I do not broadly claim providing a lead-pencil with means for suspension.

I claim—

As an article of manufacture, a wood lead-pencil provided with a perforated metal cap constructed with perforations a b, substantially as and for the purpose described.

THOMAS B. DE FOREST.
